CLAIM

The ornamental design for a bottle, as shown and described.

DESCRIPTION

FIG. 1 is a top, front and right perspective view of a bottle showing my new design;

FIG. 2 is a front view thereof;

FIG. 3 is a right side view thereof;

FIG. 4 is a back view thereof;

FIG. 5 is a left view thereof;

FIG. 6 is a top view thereof;

FIG. 7 is a bottom view thereof;

FIG. 8 is a top, front and right perspective view showing the cap and underlying portions in a separated state;

FIG. 9 is a front view shown without the cap for a clear disclosure of the underlying parts; and,

FIG. 10 is a rear view thereof.

The broken lines depict the portions of the bottle that form no part of the claimed design.

1 Claim, 5 Drawing Sheets(56)
